UNITED STATES PATENT OFFICE.

GEORGE B. SNOW, OF BUFFALO, NEW YORK.

OIL-FLAME REGULATOR FOR VULCANIZERS.

SPECIFICATION forming part of Letters Patent No. 556,702, dated March 17, 1896.

Application filed October 24, 1894. Serial No. 527,403. (No model.)

To all whom it may concern:

Be it known that I, GEORGE B. SNOW, of the city of Buffalo, in the county of Erie and State of New York, have invented certain new and useful Improvements in Oil-Flame Regulators for Vulcanizers, of which the following is a specification.

This invention relates to flame-regulating mechanism for vulcanizers using oil for fuel; and it consists in the novel combinations of parts, as hereinafter described and claimed.

In the accompanying drawings, Figure 1 is a side elevation of a vulcanizer provided with my improved flame-regulating mechanism. Fig. 2 is an enlarged elevation of the regulator-head viewed at a right angle to the position in which it is represented in Fig. 1. Fig. 3 is a vertical central section of the same on the line *a b* of Fig. 2. Fig. 4 is a plan of a diaphragm and superimposed reinforcing-plate inclosed in the regulator head or casing. Fig. 5 is a plan of the flame-controller arranged in the upper part or section of an oil-stove employed for heating the vulcanizer. Fig. 6 shows the flame-controller in end elevation and the surrounding casing in section on the line *c d* of Fig. 5.

A represents a vulcanizer supported by the jacket B upon the oil-stove C D. The regulator-head E is connected to the vulcanizer by the steam-pipe F. This head E consists of two sections 1 and 2, which may be either bolted or screwed together. Between them is tightly held a diaphragm 3, and the space beneath the diaphragm is filled with steam through the pipe F. The step-piece 4 rests centrally upon the diaphragm and controls its upward movement, preventing its being strained by accidental overpressure by striking the depending face 5 on part 1. I do not regard this as an essential feature, but it assists in preventing any derangement of the mechanism by improper usage, and the office of the step-piece may be limited to its natural function, affording a bearing-point for the step 10, which receives the pressure of the spring 9. Although any diaphragm may be used which possesses sufficient flexibility, I prefer to use one of thin copper, 3, entirely too weak to withstand the steam-pressure without support, and it has therefore superimposed upon it the reinforcing-plate 6 made

of some elastic substance, as spring-brass, with radiating cuts 7 extending nearly to its edge. An annular groove 8 is cut upon one side and near the edge to increase its flexibility and confine it to this point. As the central part of the plate is stiff, its bending when under pressure will take place only at the groove, and the movement is referred directly to its center, upon which the step-piece 4 rests, none of the movement being lost by bending of the plate between the groove 8 and its center, as would be the case if one of uniform thickness were employed. 65

Pressure upon the diaphragm is made by the spring 9, which is stiff enough to withstand the proper amount of steam-pressure and give right range of action to the diaphragm. The spring is compressed by means of the thimble 12, which is forced downward by the cap-nut 11. This is threaded upon section 1 of the casing, and for the purpose of turning it a series of holes 33 34 are made around its upper part, into which a pin may 75 be conveniently introduced.

An outer screw-cap 13 is threaded upon the part 1 for the purpose of carrying the lever 14, and when the diaphragm 3 is bulged by steam-pressure its movements will raise the lever 14, a vertically-sliding pin 16 being placed intermediate the said lever 14 and the step 10 and having a bearing on each. 80

Situated within section C of the oil-stove is a flame-controller, and an arm 17 attached thereto projects through a hole in the side of the stove. Suitable connection being made between the lever 14 and the arm 17, the flame-controller will be operated whenever the steam-pressure is high enough to bulge 90 the diaphragm against the resistance of the spring 9, and thus raise the lever 14, and the flame of the stove will be reduced so that no further rise of pressure will ensue. For the purpose of making this connection I show a chain 22, which is attached to the arm 17 and passes upward to the hook 19. The shank of the hook is threaded, and it is held by the nuts 20 21 on either side of the lever 14, and it is adjustable in length by turning these 100 nuts.

The section C of the oil-stove may be made in the form of an inverted cup floored by a perforated tin diaphragm 36, having a cen-

tral slot through which the wick-tube II passes. The flame from the wick passes upward through the slot I. The flame-controller which I show is composed of a rock-shaft 23, mounted upon taper-pointed screws 24 25 as journals and having the arms 26 27, carrying the flame-plates 28 29. These have free movement upon their points of attachment to the arms 26 27 and lean upon the 10 sides of the wick-tube H, and when the shaft 23 is rocked by raising the arm 17 the plates slide upward over the wick, partially cutting off the air supply and diminishing the flame. To prevent their displacement by falling backward, spurs 30 31 are suspended from the edges of the throat I.

A necessary condition for the satisfactory operation of this device is the accurate adjustment of the stove-wick to a certain invariable height. This may be done, by using sufficient care, without any special appliance; but as a small flame is more easily gaged than a large one I show means for raising the lever 14 to what I call the point for minimum flame. The thumb-screw 37^a is threaded into the projecting wing 37, under the lever 14, and bears against its lower side. Its length is such that if screwed upward to its full extent it will raise the lever 14 a trifle farther 30 than is sufficient to reduce the flame to the point at which it will carry the vulcanizer at a steady temperature, the flame being then reduced so that it is barely visible through the peep-hole 38 in the jacket B, the wick being adjusted by turning the thumb-wheel 39 until this effect is produced. The lever 14 is lowered by turning back the screw 37^a until a sufficiently-large flame is had for heating the vulcanizer.

40 The apparatus constructed as above described may be adjusted as follows: The spring 9 being strongly compressed by the cap-nut 11, the lamp is lighted, the wick adjusted to the points for minimum flame, and the lever 45 14 lowered to allow a large flame for heating the vulcanizer, as above described. When the required heat or pressure is obtained the nut 11 should be slackened until the steam is able to overcome the resistance of the spring 50 9 and bulge the diaphragm 3 sufficiently to reduce the flame to the proper size to prevent any further increase of heat in the vulcanizer. Then if the pressure should lower the diaphragm would relax and by the lever 14 and arm 17 increase the flame. If it should increase, the contrary action would ensue, and the temperature of the vulcanizers would thus be automatically controlled. Being thus 55 adjusted the regulator will hold the temperature of the vulcanizer at the same point for the same number of any subsequent vulcanizations; but if a change in this temperature is desired the regulator must be readjusted 60 in the manner described.

65 To render the apparatus capable of instantaneous adjustment at any time, I provide it with an index. In the screw-cap 13 is a slot

32, which is of such length and in such a position as to disclose two of the holes 33 34, which have been heretofore described as being made in the cap-nut 11. The slot 35 discloses the figures or numbers, which are suitably disposed around the lower part of the cap-nut 11, and which, as they appear, denote either the temperature or pressure of the steam in the vulcanizer, as may be preferred. When the figures show pounds-pressure the holes 33 34 may be spaced and the slot 32 be made of such a length that a movement to the extent of one hole will vary the adjustment 70 ten pounds and bring up the figures in the slot 35 which denote the change. It is now possible to adjust the regulator at any time, even before the vulcanizing has commenced, and its temperature or pressure will be accurately held without any supervision.

What I claim as my invention is—

1. In flame-regulating apparatus for vulcanizers, the combination of a casing having a flexible diaphragm therein, a pipe for conveying steam-pressure from the vulcanizer to the under side of said diaphragm, a lever mounted above the diaphragm-casing, a pin adapted to slide vertically intermediate said lever and diaphragm and having its lower portion surrounded by a spiral spring, a step-bearing for said pin and spring, a thimble placed above the spring, a nut for regulating the pressure of the spring, a flame-controller, and means for connecting the said lever and flame-controller, substantially as described.

2. In flame-regulating apparatus for vulcanizers, the combination with a flame-controller, a lever, and a connection between said lever and flame-controller, of a casing 105 containing a flexible diaphragm adapted to be acted upon by steam-pressure from the vulcanizer, a step-bearing resting centrally on said diaphragm, a vertically-sliding pin intermediate the said step-bearing and the said lever, a spiral spring surrounding the lower portion of said pin, a thimble bearing on said spring, a nut mounted on the diaphragm-casing and having a bearing on said thimble to regulate the spring, and a screw-cap also mounted on the diaphragm-casing and by which the lever is supported, substantially as described.

3. In a flame-regulating apparatus for vulcanizers, the combination of a flame-controller, a casing having a flexible diaphragm therein, a reinforcing-plate on said diaphragm, a lever mounted above the diaphragm-casing, a thumb-screw for adjusting said lever, a vertically-sliding pin between the said lever and diaphragm, a pipe for conveying steam-pressure from the vulcanizer to the under side of the diaphragm, and an adjustable connection between the lever and flame-controller, substantially as described.
